UNITED STATES PATENT OFFICE.

JAMES A. RICHARDSON, OF HALKIRK, ALBERTA, CANADA.

SHOCKER.

Application filed March 12, 1926. Serial No. 94,222.

My present invention relates to improvements in shockers for use in connection with binders of harvesting machines. The machine of the invention is of that type where-
5 in the sheaf or bundle is received from the binder in horizontal position and then turned and manipulated by automatic means to an upright position with its butt end below, and in this latter position the sheaf is
10 conveyed to the shock former or platform from which it is discharged through the operation of mechanism manually controlled. Automatic means are provided for laterally swinging the sheaf-conveyers in order
15 that they may distribute the sheaves to alternate sides of the center of the shock former or platform.

In the present exemplification of the invention I have illustrated the driving mechanism of the shocker as actuated with power from a traction wheel of the machine, and the sheaf receiving mechanism which receives the sheaf from the binder, is controlled by the weight of a sheaf whereby
25 the load imposed upon the receiving mechanism moves the latter to position for coupling with the driving mechanism.

The invention consists in certain novel combinations and arrangements of parts as
30 will hereinafter be more fully set forth and claimed.

In the accompanying drawings I have illustrated one complete example of the physical embodiment of my invention wherein
35 the parts are combined and arranged in accord with the best mode I have thus far devised for the practical application of the principles of my invention.

Figure 1 is a plan view of a shocker embodying my invention showing a portion of the binder at one side thereof from which the sheaves or bundles are received.

Figure 2 is an enlarged, outer, side elevation of the machine.

Figure 3 is a longitudinal vertical sectional view at line 3-3 of Figure 1.

Figure 4 is a detail view with parts in section of one of the endless canvas belts forming part of the conveyer for the sheaves.

Figure 5 is an enlarged, detail vertical sectional view at line 5-5 of Figure 1.

Figure 6 is a perspective detail view showing part of the operating mechanism for swinging the conveyer for the purpose of distributing the sheaves at alternate sides

of the longitudinal center of the machine and the shock-former.

Figure 7 is a detail view of the manually controlled operating parts for the shock-
60 former.

In carrying out my invention I utilize the usual type of main frame 1 for shockers and utilize the front traction wheel 2 as the power wheel for the machine, the rear end of the machine being supported by caster wheels as 3. A portion of the binder is shown at 4 with an inclined chute 5 which delivers the sheaf indicated in dotted lines in Figures 1, 3 and 5, by the letter S.
65

The sheaf is delivered to the shocker in longitudinal or horizontal position and is received from the lower free end of the chute 5 is a concavo-convex trough 6 which is located at the approximate longitudinal center of the machine, and as indicated by full lines in Figures 2 and 3 normally rests at a slight inclination above the curved floor-pan 7 of the shocker.
70

This receiving trough performs the function of a rotary carrier for the sheaves as they are successively received from the binder-chute and it is provided with spokes 8 that radiate from a hub 9 on the carrier shaft 10 which is journaled at the outer side
75 and transversely of the shocker in bearings 11 on a suitable frame. The rotary carrier is designed to make one complete revolution with its shaft 10 in the manipulation of a sheaf and the shaft is provided with a
80

mutilated gear 12 which is brought to operative position and coupled with the driving mechanism by an initial swinging movement of the carrier which movement is caused by the weight of the sheaf when the latter is deposited in the empty carrier.
85

When the weight of the sheaf swings the carrier the shaft 10 and mutilated gear 12 are turned to bring the latter into mesh with an idler pinion 13 on a stub-shaft 13' and the idler is driven from the pinion 14 on the operating shaft 14'. The operating shaft 14' is driven from a drive sprocket wheel 15 on the axle 16 of the traction wheel 2, and the chain 17 from this sprocket wheel passes over a sprocket 18 on the operating shaft 14', to drive the machine parts.
90

Thus the sheaf is deposited in the rotary carrier with its butt end to the right or front in Figure 2 and the carrier is given a complete revolution clockwise to deliver the sheaf in standing position on its butt end.
100
105
110

As the carrier turns the sheaf a tangentially arranged guide frame 19 of the carrier guides the sheaf as it is delivered in standing position between the two guide walls or plates 5 20 and 21 that extend longitudinally of the machine and are spaced at opposite sides of its longitudinal center at the rear of the rotary carrier. The sheaves pass through or between these guide walls as indicated by 10 dotted lines in Figure 3 under successive operations of the rotary carrier and are thus passed into the front openings between a pair of endless canvas belts 22 and 23 which form the conveyer for the sheaves from the 15 rotary carrier to the shock former. The endless belts of the conveyer stand in upright position and extend longitudinally of the machine, the rear ends of the belts being free to swing at their lower edges laterally of the machine to distribute the sheaves 20 at alternate sides of the longitudinal center of the machine.

Each belt passes around a pair of vertically disposed rollers 24 and 25 and the four rollers are provided with shafts 26, 26' and 27, 27'. The shafts are journaled at their upper and lower ends in pairs of extensible frames, and these extensible frames are made up of aligned bearing bars 28 and 29 that 30 are coupled together by means of a nut 30.

The two shafts 27 and 27' have stationary bearings or supports 31 through which they pass downwardly below the extensible bearing frames and these two shafts are used 35 as pivots to swing laterally the rear ends of the respective frames and thus swing the two rollers 24 laterally over the deck of the shocker. The upper ends of all the shafts remain stationary while the lower 40 ends of the two shafts 26, 26' swing laterally and thus swing their belts. Two transversely disposed arch bars 32 and 33 retain the upper ends of the shafts against lateral movement. The ends of the bars are secured to the deck of the shocker and the 45 bars are perforated to accommodate the shafts. The shafts 26 and 26' fit loosely in the perforated arch bar 32 and cotter pins 34 passed transversely through the shafts 50 above the bar permit the necessary loose movement at the upper ends of these shafts as the conveyer belts swing, as indicated in Figure 1 and also in Figure 5.

The swinging movement of the conveyer 55 on the shafts 26 and 26' as pivots is accomplished through two arms 35 and 36 attached to the undersides of the lower extensible brace bars of the roller frames, which arms have holes through which the shafts pass and to 60 permit the arms to oscillate on the shafts. The arms extend longitudinally of the shocker and at their free ends are loosely pivoted on a cross link 37 that extends toward the outer side of the shocker machine. A pitman 65 38 is connected to the link and to an

eccentric disk 39 on the eccentric shaft 40 which is journaled longitudinally of the machine beneath the main frame and provided with a sprocket 41 over which a chain 42 passes from a drive sprocket 43 on the operating shaft 10 of the carrier in order that the 70 rotary carrier and the distributing conveyer may operate in unison.

The shafts 26 and 26' form the drive shafts for the conveyer belts which are operated from the operating shaft 14 through 75 a sprocket 44 on this shaft, a chain 45 and a sprocket wheel 46 on the transversely disposed countershaft 47. Bevel-gear couples 48 and 49 between the countershaft 47 and the respective shafts 26' and 26 transmit power from the transverse shaft to the vertical shafts.

The shock former is located at the rear of the machine in position to receive the 85 sheaves as they are successively passed through the conveyer and comprises two horizontal, laterally movable platform sections 50 and 51, divided at the longitudinal center line of the machine and each reciprocable laterally from and toward the center line. The sections are moved outwardly from the center after a predetermined number of sheaves have been deposited thereon and the sheaves are discharged through 90 the opening formed by or between the separated sections.

Each section is provided with an outer wall as 52 and 53 that inclines upwardly and inwardly to retain the shock as it is being 100 formed, and these walls have cross flanges 54 at the rear, which are elevated above the platforms as indicated in Figure 3.

Each section of the laterally opening shock former is provided with a pair of 105 spaced, transversely extending rack bars as 55 and 56 that extend outwardly from the longitudinal center of the machine and are adapted to slide in the guide plates 56' secured to the main frame of the machine. 110 Each section is actuated by a pair of pinions as 57 and 58 that co-act with the rack bars and these pinions are fixed to revolve with a pair of longitudinally disposed shafts 59 and 60 journaled in suitable bearings near 115 the sides of the frame at the rear and revolved from a single cross shaft 61 through two bevel-gear couples 62 and 63.

The opening and closing movements of the 120 sections of the shock former are manually controlled from the inner side of the machine by the use of belts and pulleys located between the shaft 47 and the shaft 61. A pulley 64 on the end of the shaft 47 and a pulley 65 on the end of the shaft 61 are 125 coupled together by the loose belt 66 as indicated in Figure 7, and a second loose belt 67 which is crossed is suspended between pulleys 68 and 69 on these shafts. Normally the belts do not transmit rotary motion from 130

one shaft to the other, but belt tighteners are employed and alternately used for causing the movements of the sections.

To discharge the completed shock an idle roller 70 on the pivoted arm 71 is caused to engage the belt 67 by pulling on the rod or wire 72. This pulling movement tightens belt 67 and through the described connections the shafts 59 and 60 are revolved to accomplish the opening of the shock former. After the shock has been discharged the sections are closed together by operating the belt tightener for the belt 66 which comprises an idler roller 72 on the pivoted arm 74, and the pull wire or rod 75. The crossed belt imparts a reversed movement to the transverse shaft 61 and the longitudinal shafts 59 and 60 causing the pinions in co-operation with the rack bars to slide the sections together against to normal position as indicated in Figure 5.

Having thus fully described my invention what I claim as new and desire to secure by Letters Patent is—

25 1. The combination with a carrier-shaft and rotary carrier and a mutilated gear on said shaft, of driving mechanism including a pinion for co-action with the mutilated gear, and means whereby the weight of a sheaf will turn the mutilated gear for operative connection with said pinion.

30 2. The combination with a carrier-shaft having a mutilated gear and driving mechanism for co-action with said gear, of a carrier suspended from said shaft and balanced

whereby the weight of a sheaf thereon swings the carrier for an initial turn of the shaft for coupling the mutilated gear and driving mechanism.

3. The combination in a shocking machine 40 with a pair of endless conveyer belts, of a pivoted frame and a pair of rollers for each belt, shafts for the rollers and retaining means for the upper ends of said shafts, supports for the lower ends of one pair of 45 rollers and means for swinging the frames to cause lateral movement of the unsupported lower ends of another pair of rollers.

4. In a shocking machine the combination with a pair of laterally reciprocable shocker 50 platforms adapted to open to discharge a shock and pairs of rack bars on said platforms, of a pair of operating shafts and pinions thereon for co-action with said rack bars, means for operating the shafts, and 55 manually controlled devices for alternately operating said shafts in reverse direction.

5. The combination in a shock former comprising a pair of laterally reciprocable platforms and operating means therefor, of 60 manually controlled means for alternately reversing the movement of the operating means.

6. The combination in a shocker of a rotary carrier comprising a shaft, a hub and 65 spokes for the carrier, and a guide frame disposed tangentially of the axis of the shaft and rigid with the carrier.

In testimony whereof I affix my signature.
JAMES A. RICHARDSON.
